[57] **CLAIM**

The ornamental design for a combined breathing regulator and container for underwater use, as shown.

DESCRIPTION

FIG. 1 is a perspective view of a combined breathing regulator and container for underwater use showing my new design;

FIG. 2 is a right side elevational view thereof, with the opposite side being a mirror image and with the mouthpiece omitted;

FIG. 3 is a bottom plan view thereof, with the container omitted;

FIG. 4 is a top plan view of FIG. 3;

FIG. 5 is a front elevational view of FIG. 3;

FIG. 6 is a rear elevational view of FIG. 3.

FIG. 1

FIG. 3

FIG. 4

FIG. 2

FIG. 6

FIG. 5
